UNITED STATES PATENT OFFICE.

CHARLES A. SCHEIF, OF WILKINSBURG, PENNSYLVANIA.

WINDOW-SHADE FIXTURE.

SPECIFICATION forming part of Letters Patent No. 771,179, dated September 27, 1904.

Application filed August 7, 1903. Serial No. 168,602. (No model.)

To all whom it may concern:

Be it known that I, CHARLES A. SCHEIF, a citizen of the United States, residing at Wilkinsburg, in the county of Allegheny and 5 State of Pennsylvania, have invented certain new and useful Improvements in Window-Shade Fixtures, of which the following is a specification.

This invention relates to certain new and 10 useful improvements in window-shade fixtures, the object of my invention being to provide a simple, cheap, and effective means of attaching the blind to the window-frame and to raise and lower the same at will, at 15 the same time keeping the blind firmly in position and preventing any flapping or swinging to and fro; also, to roll the blind up even on the roller.

In the accompanying drawings I have illustrated 20 my invention, in which—

Figure 1 is a view of the blind as attached to a window-frame by means of my improved fixtures. Fig. 2 is a side view of a window-frame, showing my improved fixtures as attached thereto. Fig. 3 is a face view of one 25 of the fixtures supporting the blind to be attached to the outside of the window-frame. Fig. 4 is a top view of the same. Fig. 5 is a face view of another form of fixture used to support the blind to be attached to the outside of the window-frame. Fig. 6 is a top 30 view of the same. Fig. 7 is a face and side view of a fixture used on the inside of the window-frame. Fig. 8 is a face and side view of 35 another form of fixture used on the inside of the window-frame. Fig. 9 is a sectional view of the guide-fixtures as attached to the guide-rods and wooden stay at the lower end of the blind. Fig. 10 is a plan view of the 40 sliding fixture to be attached to one end of the wooden stay. Fig. 11 is a similar view of the permanent fixture to be attached to the other end of the wooden stay. Fig. 12 is a side view of the sliding fixture as attached to 45 the wooden stay.

In the accompanying drawings the numerals of reference designate like parts throughout the several views, in which—

The numeral 1 designates the window-frame.

2 is a bracket to be permanently attached to one side of the window-frame near the top.

3 is a lug or extension formed at right angles with the part in which the blind-roller is seated, said lug having the square opening 55 4.

5 is the bracket having the part 6, which serves as a seat for the blind-roller and having a circular opening therein to admit the guide-rod. 7 is another form of bracket used 60 on the inside of the window-frame, having the extension part 8 for seating the pintle of the blind-roller and the lug or extension 9, formed at right angles with said bracket 7 and having an opening formed therein to admit the guide-rod. In Fig. 8, 10 is another form of bracket used on the inside of the window-frame, having the extension part 11 in which to seat the blind-roller and the additional circular opening 12 to admit the guide- 70 rod.

13 is a guide-rod having a head 13' and a square portion formed under said head, so as to enter the square opening 4 in the lug 3, and thus prevent the rod from turning when being 75 tightened up. 14 is another form of guide-rod, having a head 14' and a bent portion near said head, so as to enter and become seated in the circular opening in the lug 6. On the lower ends of these guide-rods 13 and 14 is formed 80 a threaded portion to receive a nipple or screw-cap 20.

15 is a guide-sleeve having the four lugs 16 to be bent around the wooden stay 19 and an extension part 17, formed with an opening to 85 admit the guide-rods 13 or 14.

18 is a sharp extension on the guide 15', which when bent at right angles will fasten into the wooden stay and hold said guide firmly in position.

20 is a screw-cap or nipple to be attached to the threaded end of the rods 13 or 14 and serves as a means of tightening and taking up the slack in said rods.

The brackets 2 having first been fastened to 95 the top of the window-frame at either side, the guide rod 13 is then slipped through the opening 4 in the lug 3, being prevented from going clear through by the head portion, and is then secured to the bottom of the window-frame at 100

the side by a staple or screw-eye, the head of the screw-cap or nipple 20 having a bearing on said screw-eye.

For the inside of the window-frame I use 5 either the bracket shown in Fig. 7, with the straight rod attached, or the one shown in Fig. 8, having the bent rod, both being modifications of my invention.

By means of the guide-rods 13 and guide- 10 sleeves 15, adjusted on the wooden stay 19 at the lower end of the blind, I can keep the blind from flapping or moving to and fro when being raised or lowered and also prevent the blind from being rolled crooked. The guide- 15 sleeve 15 (shown in Fig. 10) is made to slide back and forth on the wooden stay 19, so as to regulate the distance between the guide-rods and prevent any binding of the part 17 against said rods. Each bracket is provided 20 with nail or screw holes 21 for fastening onto the window-frame.

Having thus fully shown and described my invention, what I claim as new, and desire to secure by Letters Patent, is—

In a window-shade fixture, the combination 25 with the casing, the upper brackets having the open and closed bearings respectively for the shade-roller and the portion to receive the upper end of the guide-rods, the guide-rods, fastenings for securing the lower end of the guide- 30 rods to the casing, the shade, the strip at the lower end of the shade, the guide-plates each having the sharp extension to engage the strip, the lugs to fold over the edges of the strip and the sleeves to fit on the guide-rods and guide 35 the shade in its movement.

In testimony whereof I affix my signature in presence of two witnesses.

CHAS. A. SCHEIF.
